UNITED STATES PATENT OFFICE

92,405

DESIGN FOR A BOTTLE COLLAR OR SIMILAR ARTICLE OF MANUFACTURE

Leo Klebanow, New York, N. Y.

Application November 2, 1933, Serial No. 49,638

Term of patent 3½ years

To whom it may concern:

Be it known that I, LEO KLEBANOW, a citizen of the United States of America, residing at New York, in the county of New York, and State of New York, have invented a new, original, and ornamental Design for a Bottle Collar or Similar Article of Manufacture, of which the following is a specification, reference being had to the accompanying drawing, forming part thereof,

I claim:

The ornamental design for a bottle collar or similar article of manufacture substantially as shown.

LEO KLEBANOW.
